G. C. NELSON

VACUUM FEED SYSTEM

Filed June 14, 1920

UNITED STATES PATENT OFFICE.

GUSTAVE C. NELSON, OF MOLINE, ILLINOIS, ASSIGNOR TO BORG & BECK COMPANY, OF MOLINE, ILLINOIS, A CORPORATION OF ILLINOIS.

VACUUM-FEED SYSTEM.

Application filed June 14, 1920. Serial No. 388,755.

To all whom it may concern:

Be it known that I, GUSTAVE C. NELSON, a citizen of the United States, residing at Moline, in the county of Rock Island and 5 State of Illinois, have invented certain new and useful Improvements in Vacuum-Feed Systems, of which the following is a specification.

This invention relates to fuel feed systems for explosive engines and it is particularly useful as an accessory to an automobile or truck engine.

The primary object of the invention is to provide means of simple and substantial 15 construction and comprising comparatively few parts for connection with the fuel supply tank and the engine whereby a constant and regular gravity fuel feed to the engine will always be maintained.

Further objects of the invention are to prevent the fuel from being drawn from 20 the inlet into the vacuum connection by the suction from the engine; to avoid delicate connections and complicated operating parts; to insure a constant and regulated 25 feed to the engine; and to provide a reserve supply of fuel for emergency use.

In the accompanying drawing I have illustrated a selected embodiment of the invention in a vertical sectional view and referring thereto 1 is the liquid fuel receiving chamber and 2 is the feed chamber. These chambers are contained within a cylindrical tank 3 having a top 4 and a semi-spherical bottom 5. A partition 6 of inverted cup-shaped form is secured within the tank above the bottom 5 and spaced from the side wall of the tank to form with the bottom 5 the feed chamber 2. A tube 7 is connected to the top of the partition 6 and projects through the top 4 of the tank to form a vent for the feed chamber. A float 8 is carried by a sleeve 9 which fits loosely upon the tube 7 and is provided at its upper end with a valve disk 10. The disk is adapted to seat against nipple 11 which projects inwardly from the top 4 and communicates with and forms part of the connec-

tion 12. The nipple 11 is connected with the intake manifold of the engine by a pipe (not shown) suitably engaged with the connection 12. An inlet nipple 13 projects inwardly from the top 4, below nipple 11, and communicates with and forms part of the connection 14 which is connected by a pipe (not shown) in a suitable manner to the supply tank usually located at the rear of the car. An air vent 15 is located in the top 4 and is preferably provided with a pet cock 16. A conduit 17 is supported in an opening in the top of the partition 6 and is provided at its lower end with a flap valve 18 to admit liquid fuel from the receiving chamber 1 to the feed chamber 2, and from the latter the fuel flows through a pipe 19 to the carburetor. A by-pass 20 provided with a valve 21 may be provided to connect the receiving chamber 1 with the carburetor feed pipe 19, to insure a reserve supply of liquid fuel for emergency purposes.

My invention provides an apparatus of very simple construction which is free from delicate and complicated parts and in which the movable parts are reduced to a float operated cut-off and a valve. This simplicity of construction not only enables the apparatus to be made in a substantial form at comparatively low cost but it reduces to a minimum and practically eliminates entirely all liability of the apparatus wearing out or getting out of order. The float operates freely on the tube 7 and its control of the cut-off valve disk is supplemented by the suction of the engine so that the buoyant action of the fuel in the receiving chamber is not entirely depended upon for the operation of the cut-off. When the cut-off 10 approaches close to the nipple 11 the suction of the engine will lift the cut-off and the float and close the nipple and when the suction is thus cut off the inflow of fuel from the supply tank ceases. This utilization of the suction to effect the cut-off when the float has lifted the cut-off disk in adjacent relation to the nipple 11 avoids the necessity for depending entirely upon the

level of the liquid in the receiving chamber to effect the cut-off and also prevents any fluttering action of the cut-off valve which might result therefrom. And the suction 5 also holds the cut-off disk in operative engagement with the nipple even after the level of the liquid has lowered beyond the point where it will, through the medium of the float, hold the cut-off disk against the 10 nipple, so that fluttering action of the cut-off valve is avoided when this valve is opened as well as when it is closed and in each instance the movement of the cut-off valve is quickened to provide a highly efficient operation.

The float sleeve is loosely mounted on the vent tube 7, which forms a guide therefor, so that it will operate freely and easily 20 under the influence of the liquid in the receiving chamber in any service position of the tanks, and the float and the cut-off valve disk and connecting sleeve are free to revolve on the tube 7 so that, as I have found in commercial use of the invention, the upper 25 face or seat of the cut-off valve disk 10 keeps clean and capable of tightly closing the nipple opening. This manner of loosely mounting the cut-off valve disk also enables it to find its seat and seat squarely and properly 30 in any service position of the tank regardless of any minor imperfections of workmanship or in the adjustment of parts.

I prefer to extend the inlet nipple 13 a sufficient distance below the suction nipple 35 11 and to locate the disk with relation to the float to insure cutting off the suction before there is any opportunity for the suction drawing fuel direct into the vacuum nipple from the fuel inlet and for this purpose I also prefer to cut the lower end 13' 40 of the inlet nipple 13 angularly with the longer side thereof located opposite the nipple 11.

The by-pass 20 forms a convenient means 45 for maintaining a small reserve supply of fuel sufficient to start the engine when the feed chamber and the receiving chamber are empty and to continue the engine in operation while the receiving chamber is being 50 filled, thus avoiding the necessity for priming the apparatus in the manner now customary in these systems.

I have found in practical experience that the fuel feed systems now in general use 55 sometimes fail on long or steep up-grades because the receiving chamber does not fill fast enough to maintain a supply in the feed chamber. In the practical use of my invention I have found that these difficulties are entirely eliminated because of the free action of the float and cut-off valve, and the rapid operation and quick movement of this valve due to the utilization of the suction of the engine in closing the valve and in holding the valve closed until the level

of the liquid in the receiving chamber has lowered so that the valve may quickly drop free and away from the suction nipple a limited distance. This is important because it promotes the efficiency of fuel feed systems of this general type and avoids a very serious difficulty and disadvantage to which they have heretofore been subject.

It will be apparent to those skilled in the art that my invention may be embodied in other forms than the selected form herein illustrated and I reserve the right to make all such changes in the form, construction, proportion and arrangement of parts as fairly fall within the scope of the following 80 claims.

I claim:

1. In a vacuum feed system, a tank comprising a receiving chamber and a feed chamber, a valved communication between said chambers, a vacuum producing connection to the receiving chamber comprising a nipple projecting inward from the top of said chamber, a float operated disk cut-off to engage said nipple and close said connection, and a liquid fuel supply inlet in the top of the receiving chamber comprising a nipple projecting into the receiving chamber from the top thereof and having its lower end located below the end of the nipple in the vacuum connection and cut angularly in relation to its length and with the longer side located opposite said vacuum connection nipple.

2. In a vacuum feed system, a tank having a receiving chamber and a feed chamber, a valved communication between said chambers, an outlet pipe connected to said feed chamber, and a valved by-pass connecting said outlet pipe with the receiving 105 chamber.

3. In a vacuum feed system, a tank having a bottom, an inverted cup-shaped partition secured within the tank above the bottom and spaced from the side wall of the tank, said partition dividing the tank into a receiving chamber and a feed chamber, a valved communication between said chambers, means for admitting liquid fuel into the receiving chamber, and an outlet pipe connected to the feed chamber.

4. In a vacuum feed system, a tank having a bottom, an inverted cup-shaped partition secured within the tank above said bottom and spaced from side wall of the tank, said partition dividing the tank into a receiving chamber and a feed chamber, a valved communication between the receiving chamber and the feed chamber, means for admitting liquid fuel into the receiving chamber, an outlet pipe connected to the feed chamber, and a valved by-pass connecting said outlet pipe with the space between the partition and the side wall of the tank.

5. In a vacuum feed system, a tank having

a semispherical bottom, a partition of inverted cup-shaped form secured within the tank above the bottom and spaced from the side wall of the tank, the bottom and partition of said tank forming a feed chamber and the remainder of the tank forming a receiving chamber, a valved communication

between said chambers, a vacuum producing connection to the receiving chamber, a float operated cut-off to close said connection, and a liquid fuel supply inlet to said receiving chamber. 10

GUSTAVE C. NELSON.
